UNITED STATES PATENT OFFICE.

HECTOR LEIGHTON DAVIES, OF GOWERTON, NEAR SWANSEA, ENGLAND, AND SAMUEL REES COUND, OF ABERAVON, WALES.

ROLLING MILL FOR THE PRODUCTION OF METAL SHEETS OR PLATES.

Application filed October 27, 1924, Serial No. 746,110, and in Great Britain November 2, 1923.

This invention relates to processes and apparatus whereby metal sheets or plates are produced by subjecting the metal in successive stages to repeated heating and 5 rolling operations, firstly in its original state in the form of a bar and thereafter, after having been folded or doubled on itself and trimmed on emerging from the preceding rolling operation, in the form of two, four 10 and usually eight-fold sheets, which constitute what is known as "boxes" and are finally trimmed, cut to the required lengths and separated.

According to the generally adopted practice, these successive stages are all performed in a single unit of apparatus comprising a furnace, rolling mill and finishing mill together with a folder and trimmer. This method is slow and dilatory and causes 20 great difficulty to the operators and unfavorably affects both output and cost of production.

According to the present invention, while each stage (by which we mean the period 25 between two successive heatings) is carried out on one rolling mill, separate apparatus viz, furnace, rolling mills, doublers and trimmers are provided for each stage and these are so arranged that the work travels 30 forward in continuity in one direction from stage to stage. At least three sets of apparatus for different stages are provided.

It has also been suggested, though we believe it has never been put into practice, 35 at any rate in Great Britain, to provide a large number of rolling mills so that, generally speaking, the work continually passes from one to another both in the same stage and in different stages. The disadvantages 40 of this are that rolls in fact have slightly different contours and work emerging with the contour given by such rolls should, if it is not to be reheated, again be placed in rolls on the same contour, otherwise undesirable 45 strains arise. This is aggravated if one set of rolls is continually occupied with work fresh from the furnace, while the next set is similarly occupied with work which has cooled during one re-rolling, and the 50 next by still cooler work, since different expansions occur in the rolls owing to the changes of temperature which further affect the contours. Furthermore this arrangement of multiple rolling mills requires ex-

cessive floor space which adds to the cost of 55 production.

Other suggestions have been made by which the work is passed through a plurality of rolling mills in all its stages without reheating, or is re-rolled after doubling 60 without reheating; or the sheets are rolled first and then in pairs without reheating; but these differ from the present invention in which rolling, whether singly or in pairs, takes place immediately after the sheets 65 have come from the furnace and before any intermediate operations have been performed, and rolling singly, in pairs, in fours etc. are each performed on different rolling mills.

The present invention avoids these difficulties by subjecting the work at each stage to the action of one set of rolling mills only, while greatly facilitating out-put by constructing the apparatus so that each stage 75 is carried out entirely separately and the work moves steadily forward.

Furthermore in the apparatus and method at present generally adopted, a number of folding mills, it may be performing different stages, are arranged on the same shaft. 80 This leads not only to great strain on the shaft, but to great difficulty in carrying out the rolling processes. For these reasons we propose, when more than one unit of apparatus is employed, to arrange such units 85 in pairs, symmetrically in relation to the driving means and in such a manner that the respective rolling mills of the two units performing the same stage in the sequence of operations are placed in axial alignment opposite each other. While the mills performing different stages in each unit can thus be driven each by its separate driving shaft, the arrangement allows the corresponding mills of the two units which operate under like working conditions to be coupled in pairs on the same shaft.

Referring to the drawings, which form part of this specification, the figure represents, as an example, a plant with two units 100 arranged according to the present invention.

Each of these units comprises symmetrically arranged opposite each other a furnace A, a roughing mill B, a doubler and 105 trimmer C, and an intermediate furnace A¹, an intermediate rolling mill B¹, a doubler and trimmer C¹, a second intermediate fur-

nace A², rolling mill B², and doubler C², and finally a finishing furnace A³, and a finishing mill B³.

The two roughing mills B, B, the two intermediary mills B¹, B¹, and the two further intermediate mills B², B², and the two finishing mills B³ are mounted in pairs on parallel shafts, D, D¹, D², and D³ respectively, which shafts are, centrally between the two mills, driven by spur and belt gearing from the engine or motor E.

The raw material in the form of bars, after being heated in the furnace A is passed through the roughing mill B, then doubled and trimmed at C. The twofold sheet is now subjected to the second stage of operations by being re-heated at A¹, and then sent first through the intermediary mill B¹ and then on to the doubler and trimmer C¹ where the double sheet is folded into four folds. The third stage now begins, and during this stage it is again re-heated at A², rolled in the mill B² and folded into eight folds and trimmed at C², and the eight fold sheets starting now on their final stage of operations are re-heated at A³, and finally rolled in the mill B³.

By means of this new apparatus it is estimated that "boxes" can be produced with a very considerable reduction of the labour formerly required, and that the cost of plant for a given output will also be substantially reduced.

We claim:—

1. A rolling mill installation, comprising a prime mover; a pair of furnaces at opposite sides thereof; a plurality of pairs of rolling mills disposed one after another beyond the prime mover, the mills of each

pair having a shaft common thereto and whereon they are mounted in symmetrical relation to each other at opposite sides of a median line which intersects all the shafts centrally; gearing for driving the several shafts from the prime mover; a pair of 45 doublers associated with each pair of mills and disposed symmetrically with relation thereto and at opposite sides of the median line; and a pair of furnaces between each pair of doublers and the succeeding pair of mills and likewise disposed at opposite sides of said line.

2. A rolling mill installation, comprising a prime mover; a plurality of pairs of rolling mills disposed one after another beyond the prime mover, the mills of each pair having a shaft common thereto and whereon they are mounted in symmetrical relation to each other at opposite sides of a median line which intersects all the shafts centrally; 55 gearing for driving the several shafts from the prime mover; and a pair of doublers associated with each pair of mills and disposed symmetrically with relation thereto and at opposite sides of said line.

3. A multi-stage rolling mill installation for producing multifold metal sheets and plates, comprising two units of apparatus arranged in pairs and including rolling mills, and driving means therefor; the respective rolling mills of the two units performing the same stage in the sequence of operations being placed in axial alignment and coupled in pairs upon common shafts.

In testimony whereof we affix our signatures.

HECTOR LEIGHTON DAVIES.
SAMUEL REES COUND.
